UNITED STATES PATENT OFFICE.

WILLIAM J. HAGMAN, OF PHILADELPHIA, PENNSYLVANIA.

POWER-DRIVEN RAILWAY TRUCK.

Application filed June 24, 1925. Serial No. 39,353.

My invention relates to driving mechanisms, and it has particular relation to such mechanisms as are applicable to railway trucks.

5 One object of my invention is to provide a simple efficient drive for trucks, which is characterized by the absence of universal joints and complicated parts; by the ease of repair; and by its adaptability to present-day car trucks without necessitating material alterations in the same.

10 Another object of my invention is to provide means whereby the thrust of the driving element on the truck and car structure may be substantially neutralized.

15 A further object of my invention is to provide means whereby a proper working relation may be insured between the power device and the truck structure as the latter 20 swivels relative thereto.

With these and other objects and applications in mind, my invention further consists in the details of construction and operation and arrangement, hereinafter described and 25 claimed and illustrated in the accompanying drawings, wherein

Fig. 1 is a detail side elevational view of a car body and supporting truck embodying my invention;

30 Fig. 2 is a horizontal sectional view taken on the line II—II of Fig. 1;

Figs. 3 and 4 are detail transverse sectional views taken on the lines III—III and IV—IV, respectively, of Fig. 1;

35 Fig. 5 is a similar view taken on the line V—V of Fig. 2;

Fig. 6 is a fragmentary sectional view of the neutralizing link and supporting bearing, the sectional plane being taken on the line 40 VI—VI of Fig. 2;

Fig. 7 is a similar view of the connecting rod and bearing, the sectional plane being taken on the line VII—VII of Fig. 2;

Fig. 8 is an elevational view of a modification, wherein the primary source of power is a gas engine;

Fig. 9 is a detail elevational view, partially in section, of the slidable gear box of Fig. 8 and mechanism directly connected therewith;

50 Fig. 10 is a plan view of the structure of Fig. 9;

Fig. 11 is a side elevational view, partially in section, of the structure of Fig. 10;

Fig. 12 is a transverse sectional view taken 55 on the line XIII—XII of Fig. 9; and

Fig. 13 is a view similar to Fig. 8, but showing a slightly modified construction.

Referring to Figs. 1 to 7, inclusive, a truck 1 of conventional design is mounted on axles 2 and 3 having pairs of wheels 4 and 5, respectively. The ends of the axles 2 and 3 are provided with cranks 6—7 and 8—9 respectively. The cranks 6—8 and 7—9 may be respectively connected by sets of side bars 11 and 12 which are journaled on pins 13 extending from said cranks. The side bars 11 and 12 may be driven by a pair of power devices 14 and 15 which, for purposes of illustration, may take the form of steam engines. Since the power devices 14 and 15 are substantially identical in construction, the former only will be hereinafter described in detail.

The power device 14 comprises a casting 16, a lower portion of which is formed into a cylinder 17 and a valve chest 18. The latter is respectively connected through flexible piping 19 and 21 to a source of steam and to an exhaust port (not shown). The flexibility of the piping 19 and 21 eliminates the necessity for the usual universal joints with their attendant disadvantages. An upper portion 22 of the casting 16 is provided with spaced shoulders 23 and 24 (Fig. 3) which slidably engage shoulders 25 and 26, respectively, of a frame 27 that is secured by bolts and clamping plates 28 and 29 to beams 31 and 32. A second pair of beams 33 and 34 in cooperation with the supporting frame 27 serves to further support the power device 14. The pairs of beams 31—32 and 33—34 are so mounted on a base portion 36 of a car body 37 of customary design, that said power device 14 may be moved longitudinally thereof. The car body 37 and the truck 1 are operatively associated by means of a pivot pin 38, whereby the truck 1 may swivel with respect thereto.

A piston rod 39 extending from the cylinder 17 is secured to a cross-head 41 which is slidably mounted on shoulders 42—42 (Fig. 4) provided by the casting 16. One end of the cross-head 41 is bifurcated and provided with a pivot pin 43 for a substantially horizontally positioned connecting rod 44, the opposite end of which is mounted on a pin 45 of a horizontally rotatable crank disk 46. The connecting rod 44 and crank disk 46 are thus operative in the swiveling plane of the truck 1. When the truck 1 is in motion, there

is a slight relative movement between the connecting rod 44 and the pins 43 and 45 due to the vibration of the truck 1. In accordance with my invention, provision is made for this slight movement by a bearing of the general form shown in Fig. 7, wherein the pin 43 is provided with a flange 47 which fits in a recess 48 formed in a base 49 of a main recess 51, the latter being in a lower arm 52 of the bifurcated portion of the cross-head 41.

An upper end 53 of the pin 43 is of reduced diameter forming a shoulder 54 which engages an upper arm 55 of said bifurcated cross-head portion. Intermediate the arms 52 and 55 is mounted a sleeve 56 having a spherical outer surface 57 which slidably engages complementary surfaces 58 and 59 of opposite blocks 61 and 62. The former block is provided with a shoulder 63 which engages a recess 64 in an end portion 65 of the connecting rod 44. The end portion 65 as well as the bearing blocks 61 and 62 may be secured together by bolts 66. A washer 67 may be interposed between the base 49 of the recess 51 and a flared portion 68 of the sleeve 56. The remaining end of the connecting rod 44 is mounted on the crank pin 45 with a similar bearing. The above construction thus permits a slight rocking movement of the connecting rod 44.

A block 69 is mounted on the upper side of the crank pin 45 and it provides a pivotal mounting for one end 71 of a link 72, an opposite end 73 of which is connected through a ball joint 74 and linkage 75 to valve gear 76 of known design. The ball joint 74 may be supported by an arm 77 carried by an end portion 78 of the motor casting 16. The design of the foregoing parts is such that the rotation of the crank pin 45 by the piston rod 39 causes the steam and exhaust pipes 19 and 21, respectively, to be connected to the cylinder 17 in the usual manner.

As shown in Fig. 5, a housing 79 is mounted on a transversely extending strap portion 81 of the truck 1, and serves to enclose bevel-gear-wheels 82 and 83. The bevel gear-wheel 82 is mounted on a lower end of a vertical shaft section 84, an upper end 85 of which is secured to the crank disk 46. A portion 86 of the shaft 84 intermediate the bevel gear-wheel 82 and the crank disk 46 is journaled in a bearing 87 formed by the housing 79. The shaft section 84 may be mounted on a thrust bearing 88 of usual design in the base of the housing 79. An oil groove 89 is formed intermediate the crank disk 46 and the upper side of the housing 79 by means of a flange 91 which extends up into an annular recess 92 in the adjacent side of the crank disk 46.

The bevel-gear-wheel 83 is mounted in the housing 79 on the inner end of a horizontal shaft section 93, which is journaled in the housing 79 at 94. An outer end portion 95 of the horizontal shaft section 93 is mounted

in a bearing 96 carried on one side 97 of the truck 1. A crank 98 is secured to a projecting end portion 99 of the shaft section 93, and as particularly shown in Fig. 2, a crank pin 101 is projected therefrom so as to extend into an aperture 102 in a block 103 slidably mounted for vertical movement in a slot 104 formed in the side bar 11.

The block 103 may be resiliently centered by springs 105 and 106 which engage opposite faces of said block, the spring 106 being positioned in a recess 107 in the lower part of side bar 11. The upper spring 105 extends into a recess 108 formed in a retaining cap screw 109 adapted to the upper part of the side bar 11, said upper part being bored and threaded to receive the cap screw 109, whereby an adjustable force may be exerted on the springs 105 and 106. When the power devices 14 and 15 are running idly and the truck 1 is being carried along by the momentum of the parts, the springs 105 and 106 assure the passage of the crank pin 101 over the dead center in the proper direction. The springs 105 and 106 also serve to maintain the side bar 11 in resilient engagement with the block 103, thereby eliminating undesirable shocks and vibration.

My invention further contemplates means, whereby the thrust of the power device 14 on the truck 1 may be neutralized and whereby a correct operating relation between said power device and said truck may also be maintained upon the swiveling of the truck. One method of accomplishing this desired result is illustrated in the drawing, wherein a neutralizing link 111 has the opposite ends thereof pivotally supported in bearings 112 and 113. The bearing 112 is carried by the end portion 78 of the power device, main casting 16 and the bearing 113 is mounted on a supporting member 114 carried by the truck 1.

The bearing 113 of which bearing 112 is a duplication is disclosed in detail in Fig. 6, wherein a central bearing pin 115 is provided with a supporting flange 116 at one end fitting within a recess 117 in the supporting structure. The pin 115 is provided with a curved outer surface 118 which is engaged by a bushing 119 fitting within an aperture 121 in the end portion of the compensating link 111. The compensating link 111 may be retained in position on the pin 115 by means of a clamping plate 122 and nut 123 on the upper end thereof. By reason of this construction, a slight relative movement is permitted between the compensating link 111 and the pin 115, whereby the vibration of the truck 1 may not be transferred to the car body 37 through the compensating link 111.

The supporting member 114 for the bearing 113 is mounted on the transverse portion 81 of the truck 1, so as to be eccentric with respect to the pivot bolt 38. As a result, when

the truck 1 swivels, the power device 14 is moved on its ways 25—26 longitudinally of the car body 37 an amount sufficient to maintain a proper working relation between the cross-head 41 and the crank disk 46. The supporting member 114 may comprise the quadrant of a sphere as shown in Figs. 1, 2 and 5, whereby the force of the compensating link 111 may be absorbed equally for all operating positions of the truck 1.

The power device 15 is operatively associated with the opposite side bar 12 through mechanism 124 which is substantially identical to that interconnecting the power device 14 and the side bar 11. A compensating link 125 is also employed for the same purposes as the link 111. The crank 98 for driving the side bar 11 and a crank 126 for driving the side bar 12 are disposed in 90° relation.

When a main control rod 127 for the valve gear 76 is actuated so as to cause the passage of steam from the pipe 19 to the cylinder 17, the cross-head 41 is reciprocated in the usual manner. As a result, power is transmitted therefrom to the wheel axle 2 through the connecting rod 44, crank disk 46, shaft sections 86 and 93, crank 98, side bar 11, and crank 6. Inasmuch as the control rod 127 is also connected to the valve gear (not shown) of the power device 15, power is similarly transmitted to the side bar 12. As noted above, the thrust of the connecting rod 44 on the truck 1 and the casting 16 incident to the operation of the power device 14 is neutralized by the link 111, and the link 125 performs the same function for the power device 15. Moreover, when the car body 37 traverses a curve, the resulting swiveling of the truck 1 relative to the power apparatus 14 tends to cause the working relation therebetween to vary, but this is also avoided by the compensating link 111, and the link 125 performs the same function for the power apparatus 15.

In some cases, it may be more desirable to employ gas instead of steam as a motive fluid. The application of my invention to such motive fluid is illustrated in Figs. 8 to 12, inclusive, wherein a gas engine 129 is mounted on a forward end 131 of a car body 132. A transmission box 133 of usual design is pivotally mounted on bearings 134 and 135, which respectively support shaft sections 136 and 137. A driving shaft 138 extends between the gas engine 129 and the transmission box 133.

The shaft section 136 is connected through a gear box or so-called power device 139 with a crank disk 141 corresponding to the crank disk 46 of Fig. 1. The crank disk 141 may be mounted on a swiveling truck 142 and it is connected with a side bar 143, as in the preceding figures. The power apparatus 139 comprises a casing 144, which is mounted for longitudinal movement in ways 145 on the car

body 132. A depending portion 146 affords a bearing for a vertical shaft 147, the lower end of which carries a crank disk 148 and pin 149. A connecting rod 151 has one end thereof mounted on the pin 149 by means of a bearing 152 which is designed to permit a slight relative movement between said pin 149 and said connecting rod 151. The opposite end of the connecting rod 151 is mounted on a crank pin 153 by means of a similar bearing 154.

The upper end of the vertical shaft 147 carries a bevel gear-wheel 155 which is adapted to mesh successively with bevel gear-wheels 156 and 157. The bevel gear-wheels 156 and 157 are mounted on an inner end 158 of the shaft 136 and spaced by a sleeve 159. Bearings 161 and 162 serve to support the shaft end portion 158 immediately adjacent to the bevel gear-wheels 156 and 157, respectively, said bearings being mounted on a cover member 163 slidably mounted on the casing 144.

A hand wheel 164 is mounted on a shaft 165 which is journaled in bearings 166 and 167 carried by the cover member 163 and it is provided with a threaded portion 168 which engages a nut portion 169 of said cover member 163. Collars 171 and 172 are spaced on opposite sides of the nut portion 169, so that when the hand wheel 164 is turned in one direction, the cover member 163 is actuated to cause the bevel gear-wheel 156 to mesh with the bevel gear-wheel 155. When the hand wheel 164 is turned in the opposite direction, the bevel gear-wheel 157 is carried to mesh with the main bevel gear-wheel 155. Thus, the direction of rotation of the shaft 147 may be controlled and hence the direction of movement of the truck 142.

When it is desirable to control substantially simultaneously the direction of operation of the shaft section 147 of the power device 139 and a corresponding shaft section 173 of a power device 174 (Fig. 8), the shaft 165 is splined at 175 to a shaft 176 which is adapted to move a cover member 177 and thereby control the direction of operation of the shaft 173 in the manner described above for the power device 139. The splined connection 175 between the shaft sections 165 and 176 permits such relative movement between the slideable power devices 139 and 174 as may obtain when the truck 142 swivels with respect thereto.

The vertical shaft 173 is similarly associated with a side bar on the opposite side of the truck 142, but in 90° relation thereto. As will be apparent, by connecting each power device to one side only of the truck 142, the lost motion of each unit is absorbed and this is also true for the structure of the preceding figures.

A compensating link 178 has one end pivotally mounted on the depending portion 146 of the slideable power device 139. The other

end is connected to a bifurcated end portion 179 of a block 181 mounted on the truck 142. Thus, the thrust of the connecting bar 151 is neutralized. A similar compensating bar 182 is also provided for the other power unit 174. The power devices 139 and 174 are retained by the compensating bars 178 and 182, respectively, in proper working relation to the truck 142 as the latter swivels. The operation of this construction is otherwise as described for that of the preceding figures.

The structure illustrated in Fig. 13 is very similar to that set forth in Figs. 1 to 7, inclusive, inasmuch as a pair of steam engines 183 and 184 are employed rather than the gas engine 129 of Fig. 8. The general operation of this embodiment of my invention being substantially as described in said figures, further description is deemed unnecessary.

20 Reference is here made to my co-pending divisional application, Serial No. 103,289, filed April 20, 1926.

While I have shown several forms of embodiments of my invention, for the purpose 25 of describing the same and illustrating its principles of construction and operation, it is apparent that various changes and modifications may be made therein without departing from the spirit of my invention, and I desire, therefore, that only such limitations shall be imposed thereon as are indicated in the appended claims or as are demanded by the prior art.

I claim:

35 1. A pair of mechanically interconnected traction elements having a swiveling movement, and a pair of power units having a longitudinal movement respectively associated with said traction elements.

40 2. A plurality of traction units mechanically interconnected, a supporting truck therefor, a body, and a plurality of power units supported by said body and operatively associated with said traction units, respectively, said power units being bodily movable relative to said truck when said traction units move in a predetermined manner.

50 3. A truck having a pair of axles, a body, and a pair of power units slidably mounted on said body and operatively associated with said axles, respectively, said power units being movable upon the swiveling of said truck.

55 4. A movable structure having a plurality of axles, a pair of power units having a movement different from said structure, and means operatively associating said power units and said axles, respectively, whereby power may be supplied to opposite portions of said axles.

60 5. A truck having a plurality of pairs of wheels, sets of side bars operatively associating said wheels, a body, a power device mounted on said body, and means operatively associating said power device and one set of

said side bars, said device being movable upon the swiveling of said truck. 65

6. A structure having an axle, a driving crank carried by said structure, a driven crank, and horizontal and vertical shaft sections extending between said cranks. 70

7. A truck having horizontal and vertical shaft sections, cranks for said shaft sections, and a driving motor operatively associated with one of said cranks and movable relative thereto upon a predetermined movement 75 of said truck.

8. In combination, a body, a power device slidably mounted thereon, and a truck carrying a crank disposed eccentrically of the swiveling point of said truck, said crank and 80 said device being operatively associated.

9. A truck, a structure having a pivotal connection therewith, a shaft disposed eccentrically of said pivotal connection, and a power device having a predetermined bodily 85 movement relative to said shaft operatively associated therewith.

10. A movable structure, a body, means for pivotally mounting said body on said structure, a power device having a predetermined movement longitudinally of said body, a driven element mounted on said structure, and means operatively associating said device and said element, said device being movable only when said structure is turned with respect thereto. 95

11. A truck having a driven crank, a body mounted on said truck, and a power device carried by said body having an operative connection with said crank, said device being 100 movable bodily when said truck swivels with respect to said body.

12. A truck, a member, means for pivotally interconnecting the same, a driven element, a power device mounted on said member, means for operatively associating said device and said driven element, a traction element, and mechanism operatively associating said driven element and said traction element, said device being movable bodily relative to said truck upon the swiveling thereof. 105

13. A truck having a traction element provided with a crank, a second crank operatively associated therewith, a third crank having a driving connection with said second crank, 115 and a power device operatively associated with said third crank, said device being movable when said truck is moved in a predetermined manner.

14. A truck having a pair of axles, side bars interconnecting corresponding opposite ends of said axles, a member pivotally mounted on said truck, a power device mounted on said member, and mechanism for interconnecting said power device and one set of said side bars, said device being bodily movable only when said truck swivels. 120

15. A truck having pairs of axles, the oppo-

site ends of which are respectively interconnected by sets of side bars, a power device mounted for slidable movement only when said truck swivels, and means for operatively connecting said power device with one of said sets of side bars.

16. A movable structure having a pair of axles, sets of side bars for mechanically interconnecting corresponding opposite ends of said axles, a power device, means for operatively associating said device and one of said sets of side bars, said means including a vertical shaft, and a second power device having a connection with the other of said sets of side bars, said devices being so movable relative to said structure as to maintain correct working conditions for various positions of said structure.

17. In combination, a car body, a truck movable relative thereto, a pair of axles, sets of side bars respectively connecting corresponding ends of said axles, a pair of motors slidably mounted on said car body, and shafting interconnecting said motors and said sets of side bars, respectively, said motors being movable only upon the swiveling of said truck.

18. In combination, a supporting body having interconnecting vertical and horizontal shaft sections, an axle having an operative connection with one of said sections, and a motor operatively associated with the other of said shaft sections, said motor being bodily movable upon a relative bodily movement between itself and said axle.

19. A truck supporting horizontal and vertical shaft sections, an axle positioned to be driven by one of said shaft sections, a driving motor operatively associated with the other of said shaft sections, said motor being bodily actuated when said truck is moved in a predetermined manner.

20. A truck having a pair of axles, side bars respectively connecting corresponding ends of said axles, shafts including horizontal and vertical sections respectively connected to said side bars, and a pair of power devices having a driving connection with said shafts respectively, said power devices being bodily movable upon the swiveling of said truck.

21. A movable member, a bodily movable power device, and means whereby said power device may be actuated relatively of said member upon a movement of the latter, said means comprising an element positioned in the plane of movement of said member.

22. A movable structure, a bodily movable power device, and a neutralizing link operatively associating the same and adapted to cause a movement of said device upon a movement of said structure.

23. A swiveling structure, a longitudinally movable power device, and a member pivotally mounted on said device and said structure, whereby said power device may be

moved upon the swiveling of said structure.

24. A movable power device, a swiveling truck, and a link adapted to cause a bodily movement of said device upon the swiveling of said truck.

25. In combination, a swiveling structure, a bodily movable power device, and a compensating member, the ends of which are mounted on said power device and said structure, the latter mounting being eccentric to the swiveling point of said structure.

26. A truck having a swiveling pin, a body carrying a movable power device, and a compensating link having the ends thereof pivotally mounted on said device and said truck, the latter mounting point being eccentric to said swiveling pin.

27. In combination, a swiveling truck, a car body, a power device slidable on said car body, means whereby said truck may be driven by said power device, said means including connecting rod and crank mechanism, and means for insuring a proper operating relation between said device and said truck as the latter swivels.

28. In combination, a swiveling truck, a slideable engine, a crank on the truck, a connecting rod extending between said crank and said engine, and neutralizing means for preserving the proper working relation between said engine and said truck as the latter swivels.

29. In combination, a swiveling truck, a body, two reciprocating engines movably supported by said body, a pair of crank shafts mounted on said truck adapted to be actuated by said engines, respectively, said engines having 90° relation one with the other, and means for insuring a desired operating relation between said engines and said truck.

30. A swiveling truck, a pair of reciprocating power devices having driving connection with said truck and movable relative thereto, means for maintaining said devices in 90° relation one with the other, and means for maintaining the desired operating relation between said devices and said truck when the latter swivels.

31. In a device of the class described, a truck having driving wheels, a vertical shaft, a horizontal shaft, gearing for associating said shafts, a side bar for operatively associating said driving wheels, and crank mechanism for interconnecting said side bar and said horizontal shaft section.

32. In combination, a car body, a supporting truck, power apparatus having a driving connection with said truck slidably mounted on said car body, means for insuring a proper working relation between said power apparatus and said truck as the latter swivels, and means for controlling the direction of operation of said power apparatus.

33. In combination, a body, a supporting truck, power apparatus having a driving con-

nection with said truck slidably mounted on said body, means for insuring a proper working relation between said power apparatus and said truck as the latter swivels, and means carried by said power apparatus for controlling the direction of operation thereof.

34. A truck having a pair of spaced wheels interconnected by a side bar, said bare having a recess, an apertured block slidably mounted therein, means for resiliently centering said block, and a driving crank having a projecting pin disposed in the aperture of said block.

35. In combination, a swiveling structure, a supporting member, a motor slidably mounted on said supporting member, said motor having a driving connection with said swiveling structure, means for insuring a proper driving relation between said motor and said swiveling structure as the latter turns, and flexible means for supplying energy to said motor.

36. In combination, a swiveling structure, a supporting structure, a motor slidably mounted on said supporting structure, said motor having a driving connection with said swiveling structure, means for insuring a proper driving relation between said motor and said swiveling structure as the latter turns, and flexible piping operatively associated with said motor.

37. A swiveling structure, a supporting structure, a power device bodily movable on said supporting structure, a link having one end pivoted on said device, and a casing constituting the quadrant of a sphere affording a pivotal mounting for the end of said link, said casing being mounted on said swiveling structure.

38. A device of the class described comprising a car body, a truck having driving parts, a source of power attached to said car body, and means for operatively associating said source of power and said driving parts, said means including connecting rods positioned to move in a horizontal plane.

39. A car body, a truck having driving parts, a source of power attached to said car body, and means for operatively associating said source of power and said driving parts, said means including connecting rods positioned to reciprocate in the swinging plane of the truck.

40. A swiveling structure, a supporting structure, power apparatus movable on said supporting structure, a link having one end mounted on said power apparatus, and means for mounting the other end of said link on said swiveling structure, whereby the force thereof on said swiveling structure may be absorbed equally for all operating conditions thereof.

41. In combination, a truck having a vertical driving shaft section, a car body

mounted on said truck, and a power device for actuating said shaft section so mounted on said car body as to have a substantially longitudinal movement upon the swiveling of said truck.

42. In combination, a truck, a body movably mounted thereon, driving means mounted on said body, and means constituting a driving connection between said first-mentioned means and said truck, said second-mentioned means being operative in substantially the swiveling plane of said truck.

43. In combination, a truck having driving parts, a car body, a source of power carried by said car body, means for operatively associating said source of power and said driving parts including a rod operative substantially in the plane of movement of the truck, and means for insuring a proper operative relation between said truck and said source of power.

44. A body, a movable supporting truck therefor having driving parts, power apparatus movably mounted on said body, means for operatively associating said power apparatus and said driving parts, said means including a connecting rod operative in substantially the plane of the truck movement, and a compensating link also operative in the plane of movement of the truck.

45. A body constituting a movable support for a power device, a supporting truck for said body having driving parts including a crank, a connecting link for operatively associating said power device and said crank, and a compensating link for insuring a proper operating relation between said power device and said crank, the latter and said links being operative in substantially the plane of movement of said truck.

46. A truck having driving parts, a body supported thereon and providing a movable support for a power device, a connecting rod extending between said power device and said driving parts, and means for so mounting said connecting rod as to minimize the transfer of truck vibration by said rod to said body.

47. A supporting body having driving parts including interconnected vertical and horizontal shaft sections, an axle operatively associated with one of said sections, a crank mounted on the other section for operation in substantially the plane of movement of the supporting body, a motor mounted for longitudinal movement relative to said supporting body, and means also operative in said plane for operatively associating said motor and said crank.

48. A supporting body having driving parts including interconnected vertical and horizontal shaft sections, an axle operatively associated with one of said sections, a crank mounted on the other section for operation

- in substantially the plane of movement of the supporting body, a motor mounted for longitudinal movement relative to said supporting body, means also operative in said plane 5 for operatively associating said motor and said crank, and a compensating link extending between said motor and said supporting body so as to insure a desired operating relation therebetween.
- 10 49. In combination, movable power apparatus, a movable truck, and a link operative in substantially the plane of movement of said truck for insuring the bodily movement of said apparatus upon a movement of said truck, said link being so mounted as to minimize the transfer of vibration by said link from said truck to said motor.
50. In combination, a swiveling truck having driving parts including vertical and horizontal shaft sections, a body, a plurality of motors movably carried by said body, means 20 for operatively associating said motors and said driving parts, said motors being in 90° relation one with the other, and means for insuring a desired operating relation between 25 said motors and said truck, said means being positioned in one or more substantially horizontal planes.
51. A truck having a pair of wheels interconnected by a side bar provided with a recess, an apertured block slidably mounted in said recess, means for resiliently centering said block, means for adjusting said first-mentioned means, a driving shaft, and means for connecting said shaft to said block. 30
52. A truck, a car body, a motor movably mounted on said body, said truck having driving parts, means for connecting said motor and said driving parts positioned in substantially the plane of movement of said truck, means for insuring the desired operating relation between said motor and said truck, and flexible means for supplying energy to said motor. 35
